INVENTOR

Franz Wondra

UNITED STATES PATENT OFFICE.

FRANZ WONDRA, OF SCHENECTADY, NEW YORK.

INTERNAL-COMBUSTION TURBINE.

Application filed September 27, 1921. Serial No. 503,614.

My present invention relates to improvements in turbine engines of the character described in my prior Patents 1,252,369, filed October 17th, 1908, and 1,298,430, filed 5 February 27th, 1911, and has for its object the novel construction of fluid pressure generators hereinafter described.

Another object of the invention is the arrangement of small units of the turbine, 10 to form a large unit.

Another object of the invention is, to reduce the volume of the working fluid produced, reducing thereby the power of the 15 turbine.

15 This invention relates to internal combustion turbines, where the combustion takes place intermittently and at constant volume through spontaneous combustion of the charges, and where part of the heat of the 20 products of combustion is abstracted and utilized with the exhaust of the turbine for generation of steam, which in turn is mixed with the products of combustion after each discharge.

25 The production of the mixed working fluid is mechanically controlled and the expansion of the fluid is carried below the atmospheric pressure.

30 The manner in which the above objects are attained and the mode of operation is 35 fully explained in and by the following statement and is clearly illustrated by the accompanying drawings.

It is known to me, that turbines have been 35 built working with mixed fluid and at constant pressure. The work done in compressing the charge or producing vacuum in these types of turbines in proportion to the 40 power developed, is so large, that the overall efficiency of these turbines is very low.

It is also known to me that gas turbines of the constant volume type have been built, where the working-fluid consists of the products of combustion only. Turbines of this 45 type need large amounts of air for scavenging purpose and this air takes heat away, which cannot be utilized in the same turbine again.

This invention differs from all known systems of internal combustion turbines, in that 50 the working fluid is a mixture of products of combustion produced at constant volume and steam. This working fluid is produced in a plurality of fluid pressure generators 55 which are divided in groups, and while one

group discharges the working fluid against the turbine wheel, another group is being charged with fresh air and fuel charges.

During the combustion period the gases are entirely enclosed, cannot expand, and 60 part of the heat escapes into the steam jacket which surrounds the combustion chamber.

The steam in this jacket has been generated partially by the heat of the exhaust 65 of the turbine.

The potential energy of the gas and steam is changed into kinetic energy before mixing, the steam jet streams through an annular nozzle around the gas jet, whereby the steam is internally superheated, and the temperature of the gas is reduced before it enters 70 the expansion nozzle.

The air and fuel are admitted into the combustion chamber separately, the temperature in the combustion chamber is kept so 75 high as to cause spontaneous combustion of the charge.

The fuel is injected into the air in the combustion chamber, and because the whole amount for one charge cannot enter at once, 80 the combustion will not become an explosion.

The exhaust of the turbine is expanded in a low pressure turbine below the atmospheric pressure, and discharged into a regenerator, where the remaining heat is used 85 for generation of steam and heating of fuel, and finally discharged into a condenser.

The condensable part of the exhaust is 90 condensed there, and the rest is compressed by a turboblower to the atmospheric pressure and discharged.

The compression of the air is accomplished in stages, and the compressors are 95 driven by the turbine.

In the accompanying drawings

Fig. 1 is a front view of the turbine with four fluid pressure generators.

Fig. 2 is side view of the whole turbine system, the regenerator being shown in longitudinal section.

Fig. 3 is a vertical section of one of the fluid pressure generators, and a part of the turbine wheel.

Fig. 4 is a section on line 4, 4, of Fig. 3.

Fig. 5 is a section on line 5, 5, of Fig. 3.

Fig. 6 is an arrangement for cutting out

single fluid pressure generators.

Fig. 7 is an axial section of the turbine system on line 7, 7, of Fig. 1.

Fig. 8 is an arrangement for cutting out

single fluid pressure generators while the turbine is in operation.

Fig. 9, is an enlarged view of the cutting arrangements separately for steam and the products of combustion.

Fig. 10, is a front elevation of the cutting arrangement.

Fig. 11, is a side view of a combination of single turbines to a large unit.

10 In Fig. 2 the compressors and pumps of the system are shown diagrammatically only.

In this Fig., A is the internal combustion turbine.

B, is the low pressure turbine.

15 C, is the turbocompressor.

D, is the reciprocating compressor.

E, is the turbo exhauster.

F, is the regenerator.

G, is the location of the fuel pump.

20 H, is the location of the water pump.

I, is the location of the centrifugal pump.

J, is the location of the regulator.

The construction of the turbine proper is following:—

25 The casing consists of a plurality of fluid pressure generators 1, between which are inserted segments 2, (Fig. 3), forming thus a complete ring, which is inclosed by the heads 3 and 4. These heads have bearings

30 for the shaft 5, which consists of two parts, and carries the turbine wheel 6. The heads serve also as standards for the turbine, being provided with flanges which rest upon the beams 7.

35 On the hub of the head 3, is loosely mounted the cam disk 8, which has a geared periphery, and is actuated from the turbine shaft by the bevel gears 9, 10, 12 and 13, the shafts 11 and 14, the pinion 15, 40 which meshes with the geared periphery of the cam disk, reducing thus also the speed of the same relative to the turbine wheel.

Each fluid pressure generator has inlet valves 16 and 17, which are connected to lever arms 18 and 19, and an outlet valve 20, which is connected with the lever arm 21.

The heads of the casing have radially extending arms, with bearings for the shafts 22, 23 and 24. The shaft 22 is hollow, and 50 loosely mounted upon shaft 23. (Figs. 3 and 7). Upon these shafts are the lever arms 18, 19 and 21, fastened above the valves, and above the cam disk are fastened the lever arms 25, 26 and 27.

55 The longer lever arms are provided with an extending pin 28, with a roller thereon, which rolls in the cam grooves of the cam disk, sliding thus the valve into open or closed position.

60 The cam disk has cam grooves on both sides, which are set 45° ahead, relative to each side. In Fig. 1 only the center lines of the cam grooves of the other side are shown. Two of the generators, located dia-

metrically opposite, are actuated from the cam grooves of the one side, and two from the cam grooves of the other side of the cam disk.

Each of the generators has a combustion chamber 28, a mixing chamber 29, which are connected through the outlet port 30, and both chambers are surrounded by a steam jacket 31, which has a conduit 32, leading into the mixing chamber.

Adjacent the steam jacket is the air chamber 33, and fuel chamber 34, with ports 35 and 36, leading to the combustion chamber.

All these chambers, with the respective valve casing, are cast in one piece, and are surrounded by an exhaust hood 37, which is made in halves, and to which is bolted the exhaust pipe 38, delivering the exhaust of the turbine A to the turbine B for further expansion.

The ports between the various chambers are closed or opened by piston valves. The valve 16 controls the air inlet, valve 17 the fuel admission, and valve 20 the discharge of steam and products of combustion.

90 The piston valves have grooves 39, which register with the respective ports, the valves being actuated by the levers from the cam disk, to cover or uncover the ports.

95 Each revolution of the cam disk produces two charge and two discharge periods in each generator.

The turbine shaft drives the crankshaft 42 through the gears 40 and 41, which, in turn, actuates the reciprocating compressor D, the fuel pump G, the water pump H, the circulating pump I, and the regulator J. The cylinders of the reciprocating compressor are arranged in a V form, and on each side of the turbine shaft, as shown in Fig. 2. 100 105

The revolving elements of turbine B, of the turbocompressor C, and of the turbo exhauster E, are fastened directly on the shaft 5.

110 The low pressure turbine is shown as a radial turbine, the disk 43 carries the rows of buckets 44, and the stationary rows of buckets 45, are carried by the turbine casing.

The exhaust of the turbine A is delivered through the pipes 38, toward the center of the turbine B, expands here radially, and escapes into the regenerator F.

115 The regenerator has helical heating channels, into which the steam coil 46 is placed. In the center of the regenerator the fuel pipes 47 are coiled.

120 The gases escape at 48 out of the heating channels, and stream along the steam pipe 46, return at 49 along the fuel pipes 47, and escape at 50 into the condenser 51.

125 In the condenser is the coiled water-pipe 52, having discharge openings on the underside, and which is supplied with water from the pump I. The condensed water is drained off by the conduit 53. The uncondensable

part of the working fluid is removed by the turbo exhauster E, the casing of which is mounted upon the top of the condenser.

The heads 3 and 4 have water jackets, and the pump H and conduit 54 (Fig. 7) deliver water thereto. The pump H and pipes 46 convey the heated water from the jackets, and carry it through the regenerator, where it is gradually heated and evaporated by 10 the exhaust gases until it changes to steam.

The fuel pipes 47, carry the fuel from the fuel pump G through the regenerator, then through the exhaust pipes 38 and the exhaust hood, into the fuel chamber 34.

15 The turbine wheel 6, has two rows of U shaped buckets. The products of combustion are discharged through the nozzle 55, and the steam through the annular nozzle 56, into the mixing-chamber, wherefrom the mixed fluid is discharged through the nozzle 57 against the buckets of the wheel.

The segments 2, between the generators, have reversing buckets 58, and are provided with steam jackets 59. The steam generated 25 in the regenerator is conveyed therefrom by the pipes 46, and delivered into the steam jackets 59, entering therein at 60, and from there through the opening 61 into the steam jacket 31.

30 Each set of the reversing buckets carries an oval segmental bar 62, which projects in the buckets of the wheel and prevents the fluid jet from expansion before being reversed.

35 The compression of the air is accomplished in stages, first in the turbocompressor C, and then in the reciprocating compressor.

However, the air can also be compressed 40 in the turbocompressor to its final compression pressure.

The compression should be preferably as closely isothermal as possible.

The pipes 63 bring the air from the compressor into the air chamber 33.

45 The arrangements shown in Fig. 6 make it possible to cut out in some of the generators the discharge of the working fluid. The lever arm 27 is in this case loosely mounted upon the shaft 24, and is provided

50 with a coupling jaw. The respective radial arm of the head 3, which supports the shaft, is extended, and supports the fork-shaped lever 64. The clutch body 65, has a slot, in which the pin 66 of the respective shaft 55 slides.

By pulling the rod 67, the clutch body is coupled with the respective lever arm, which now imparts the cam motion to the respective shaft, and shifts thereby the valve into 60 closed and open position.

By pushing the rod 67 the clutch body is disconnected from the respective lever arm, which now slides loosely upon the respective shaft, and the valve connected to this 65 shaft remains inactive.

The connection rod 68 actuates simultaneously the feeding valve of the water pump (not shown), and accordingly the motion of the rod increases or reduces the supply of water.

70 The arrangements shown in Fig. 8 make it possible to cut off the steam discharge from some of the generators with the aid of the cam disk 8.

Upon the hub of the cam disk 8 the cam 75 disk 72 is slidably mounted, and revolves with the same. The cams of the disk 72 are located by the pin 73 relatively to the disk 8 in such a position, that the disconnection of the valves is possible only during their 80 idle periods. The pin 73 is fastened to the hub of the disk 8 and the disk 72 has a slot parallel to the turbine-shaft which engages the pin.

By pushing the disk 72 by means of the 85 lever 74 under the roller 75, which is mounted upon the push-rod 76 and connected to the crank lever 77, the cam motion withdraws the clutch body from the jaws of the lever 27, which becomes thereby idle, and does not 90 actuate the respective valve. The cams of the disk 72 change to a round onset, whereby the disconnection of the coupling is maintained.

By pulling the disk 72 by means of the 95 lever 74 from the roller 75, the spring 78 brings back the clutch body 65 into the jaws of the lever 27, whereby the respective valve is again actuated.

The arrangements as shown in Fig. 6 and 100 8 can be applied also to cut out the production of products of combustion by connecting it with the shafts 22 and 23.

One cam disk 72 operates the discharge valves and one the air valves.

At the start, before there are any exhaust gases in the regenerator, the burner 69 is lighted. By an auxiliary pump (not shown) air under pressure is supplied to the burner through the pipe 70, and fuel through the 110 pipe 71, which are ignited, and the heating gases take the same course as the exhaust gases of the turbine B.

The working cycle of the turbine is as 115 follows:

With auxiliary pumps (not shown) air under pressure is admitted in the air chamber 33, heated fuel in the fuel chamber 34, and the steam which has been generated in the above mentioned way in the regenerator, is admitted to the steam jacket 31.

The cam disk 8, is set in motion by a suitable mechanism preferably coupled to shaft 14 (not shown) whereby the air valve admits the air into the combustion chamber; further motion of the cam disk closes the air port, and the fuel valve admits fuel heated to selfigniting temperature in the combustion chamber, causing spontaneous combustion therein. Further motion of the cam disk 130

cuts off the fuel admission, the combustion now takes place in a perfectly closed chamber, part of the developed heat escapes through the walls in the steam jacket, heating the steam therein. Further motion of the cam disk shifts the valve 20, and now the products of combustion rush through the nozzle 55, and simultaneously the steam through the annular nozzle 56 approximately together in the mixing chamber, whereby the steam becomes internally superheated, and the mixed fluid rushes through the nozzle 57 against the buckets of the turbine wheel 6.

15 The flow of the fluid is reversed several times in the reversing buckets, and discharged against the wheel until it reaches the exhaust hood 37 of the generator located ahead of that one which produced the fluid 20 and escapes through the same, heating hereby the steam in the jacket 31, into the exhaust pipe 38, which conveys it to the turbine B for further expansion.

The steam pressure in the jacket 31 will be 25 almost constant, and the suction of the annular nozzle 56 will carry off the residual gases from the combustion chamber at the end of the discharge period when the gas pressure is low, thus scavenging the chamber.

30 After the discharge period the valve 20 closes the ports 30 and 32, and the air valve admits air for new combustion.

Two diametrically oppositely located generators work simultaneously, and while two 35 generators are discharging the fluid, the other two are charged, so that the impulse upon the wheel is continuous, although the action of the single generator is intermittent.

40 The turbine, being once in motion, drives the different compressors and pumps, delivering the various substances to the generators.

The turbine is designed preferably for 45 liquid fuel, but by increasing the size of the fuel pump and fuel valves it can be operated with gaseous fuel.

The number of the generators in the turbine can be varied, or the same can be designed for axial flow, or any other flow.

50 In order to make a large unit from small units, a number of turbines A, are arranged side by side, and their wheels mounted upon common shaft. Then only one turbine has the cam disk, and operates all the valves of

the turbines A. The exhaust of all the turbines A is collected and delivered to one low pressure turbine for final expansion.

What I claim as new, and desire to secure by Letters Patent of the United States, is,—

1. In a fluid pressure generator for internal combustion turbines in combination, a combustion chamber wherein combustion at constant volume intermittently takes place, means supplying separately air and fuel thereto, a steam jacket surrounding said combustion chamber, part of the heat generated by the combustion being utilized for generation of steam in said steam jacket, a gas nozzle discharging the products of combustion from said combustion chamber, a steam nozzle around said gas nozzle discharging intermittently steam from said steam jacket, the discharge of the products of combustion and the discharge of the steam occurring simultaneously.

2. In a fluid pressure generator for internal combustion turbines in combination, a combustion chamber wherein combustion at constant volume intermittently takes place, means supplying separately air and fuel thereto, a steam jacket surrounding said combustion chamber, part of the heat generated by the combustion being utilized for generation of steam in said steam jacket, a mixing chamber adjacent said combustion chamber, a gas nozzle discharging the products of combustion from said combustion chamber into said mixing chamber, a steam nozzle around said gas nozzle discharging intermittently steam from said steam jacket into said mixing chamber, the discharge of the products of combustion and the discharge of the steam occurring simultaneously, a nozzle leading from said mixing chamber and discharging the mixture of products of combustion and steam therefrom.

3. In an internal combustion turbine having a bucket wheel, a plurality of fluid pressure generators producing working fluid composed of products of combustion and steam, means discharging the working fluid against the buckets of the wheel, and means cutting out the discharging means mechanically in some of said generators while the bucket wheel is in motion.

In witness whereof I have hereunto set my hand the 26th day of September, 1921.

FRANZ WONDRA.
